(57) **CLAIM**

The ornamental design for lighting module, as shown and described.

DESCRIPTION

FIG. 1 is a front plan view of a lighting module according to a first embodiment, wherein the lighting module is a light source.

FIG. 2 is a first front perspective view of the lighting module of the first embodiment.

FIG. 3 is a second front perspective view of the lighting module of the first embodiment.

FIG. 4 is a first rear perspective view of the lighting module of the first embodiment.

FIG. 5 is a second rear perspective view of the lighting module of the first embodiment.

FIG. 6 is a rear plan view of the lighting module of the first embodiment.

FIG. 7 is a first side plan view of the lighting module of the first embodiment.

FIG. 8 is a second side plan view of the lighting module of the first embodiment.

FIG. 9 is a third side plan view of the lighting module of the first embodiment; and,

FIG. 10 is a fourth side plan view of the lighting module of the first embodiment.
